(57) **CLAIM**

The ornamental design for an equipment cover, as shown and described.

DESCRIPTION

FIG. 1 is a front, right, top perspective view of an equipment cover showing my new design;

FIG. 2 is a rear, right, bottom perspective view thereof;

FIG. 3 is a rear, left, bottom perspective view thereof;

FIG. 4 is a front, left, top perspective view thereof;

FIG. 5 is a front elevation view thereof;

FIG. 6 is a rear elevation view thereof;

FIG. 7 is a left side view thereof;

FIG. 8 is a right side view thereof;

FIG. 9 is a top plan view thereof; and,

FIG. 10 is a bottom plan view thereof.

The broken lines of uneven length shown in FIGS. 1-10 form a boundary of the claimed design. The broken lines of even length shown in FIGS. 1-10 illustrate portions of the equipment cover that form no part of the claimed design.
